(57) **CLAIM**

We claim the ornamental design for a digital video disk recorder with hard disk, as shown.

DESCRIPTION

FIG. 1 is a perspective view of the digital video disk recorder with hard disk showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a perspective view thereof, shown in an open position.
